CLAIM

I claim the ornamental design for a toilet seat cover, as shown and described.

DESCRIPTION

FIG. 1 is a top perspective view of a toilet seat cover embodying the invention.

FIG. 2 is a top plan view of the toilet seat cover shown in FIG. 1.

FIG. 3 is a right side elevational view of the toilet seat cover shown in FIG. 1, the left side elevational view being a mirror image thereof.

FIG. 4 is a front elevational view of the toilet seat cover shown in FIG. 1.

FIG. 5 is a cross-sectional view of the toilet seat cover taken through section line 5—5 of FIG. 2.

FIG. 6 is a cross-sectional view of the toilet seat cover taken through section line 6—6 of FIG. 2.

FIG. 7 is a top perspective view of a toilet seat cover that is a second embodiment of the invention.

FIG. 8 is a top plan view of the toilet seat cover shown in FIG. 7.

FIG. 9 is a right side elevational view of the toilet seat cover shown in FIG. 7, the left side elevational view being a mirror image thereof.

FIG. 10 is a front elevational view of the toilet seat cover shown in FIG. 7.

FIG. 11 is a cross-sectional view of the toilet seat cover taken through section line 11—11 of FIG. 8; and,

FIG. 12 is a cross-sectional view of the toilet seat cover taken through section line 12—12 of FIG. 8.

The present application is directed to the shape and contour of the design illustrated in the drawings. The rear and bottom views are not part of the claimed design. The cross-sectional views are included only to show the curvature of the upper surface and otherwise form no part of the claimed design.
